UNITED STATES PATENT OFFICE

WILLIAM MAYO VENABLE, OF PITTSBURGH, PENNSYLVANIA, ASSIGNOR TO BLAW-KNOX COMPANY, OF PITTSBURGH, PENNSYLVANIA, A CORPORATION OF NEW JERSEY

MEASURING APPARATUS

Application filed November 8, 1926. Serial No. 146,909.

This invention relates to measuring apparatus, and particularly to apparatus for measuring the sand and water used in the mixture of concrete.

5 As is known to those well versed in this art, the production of concrete of uniform consistency, and uniform ultimate strength, depends upon a uniform proportioning of all of the materials from batch to batch, but in 10 actual practice absolute uniformity cannot be obtained because of variations in the quality, grading and dampness of the stone, the quality of the cement, and the quality, packing and moisture of the sand. Among the greatest 15 of the variable factors are the quantities of sand and water, because of the fact that absolutely dry sand can seldom be obtained and that damp sand results in an increase in the total amount of water entering the mixture and a decrease in the actual amount of sand due to the "bulking" of the sand, as it is termed. This bulking or fluffing varies in degree according to the moisture content of the sand and may result in variations of as 25 much as 40% in the absolute amount of sand contained in a given volume.

It is known, however, that if sand be measured while saturated, that is with its interstices or void spaces filled with water, it 30 will, in its natural settling in a container or measure occupy substantially the same volume every time the operation is repeated. If the sand be also of a substantially uniform average grade, it will, when saturated, contain in each batch of uniform measured volume a uniform quantity of water, that is, if it be of substantially uniform grade, its percentage of void spaces will not vary materially if measured in a completely saturated 35 condition, and consequently the volume of water contained in a given volume will be substantially uniform. By the measurement of the sand in a completely saturated or inundated condition, therefore, both the sand and the water entering the mixture are of 40 practically constant proportions and in consequence the two most variable factors in the manufacture of concrete become practically 45 constant from batch to batch.

50 One of the primary objects of this inven-

tion is the provision of novel apparatus for carrying out, and obtaining the advantages of, the inundation method of measuring materials for concrete outlined above.

Another object of the invention is the provision of such apparatus which will make it possible to carry out the method with speed as well as accuracy on a commercial scale. 55

Still another object is the provision of apparatus of the character outlined which shall be compact as to space required, easy of installation and operation, rugged in construction, and which will minimize losses of sand and water. 60

How the foregoing, together with other objects and advantages which will occur to those skilled in the art or which are incident to my invention, are obtained, will appear from the following description of the present preferred embodiment of the invention, reference being had to the accompanying drawings thereof, wherein:

Fig. 1 is a side elevation of the apparatus as installed beneath a sand storage bin having space beneath for a concrete mixer or 75 for a conveyor or truck;

Fig. 2 is an enlarged elevation, with parts in section, of the measuring and dumping receptacle;

Fig. 3 is a plan view of the receptacle; 80
Fig. 4 is a view of the complete apparatus taken from the left of Fig. 1; and

Fig. 5 is a plan view of the water measuring or charging tank 20.

Referring first to Figs. 1 and 4, it will be 85 seen that I have illustrated the bottom portion of a sand storage or supply bin 2, which is supported from a framework indicated generally by the reference numeral 3. Beneath the bin and between the legs 4 and 5 90 of the supporting structure there is, in accordance with common practice, sufficient space for the placing of a concrete mixer or the insertion of a conveyor or a truck body, and it is to be understood that there may be mounted 95 on the same supporting structure, supply bins for stone or other ingredients in a manner now well known in the art.

The apparatus of the present invention may be supported in any convenient manner 100

from the framework, or from the bin itself, or partly from each as here shown. Pivotally mounted at 6, on depending supports 7, 7, hung from a member 8 attached to the bin, is a measuring and dumping container or receptacle 9, it being understood of course that there is a pivot 6, and supporting frame 7, 7, on each side of the receptacle.

The water supplying apparatus is shown at the left of Figs. 1 and 4, this apparatus being here shown as supported partially from the bin and partially from the framework. located at a level above the measuring container 9 is the charging tank 20 which is filled at the top through pipe 21 from any convenient source of water supply, and which is discharged from the bottom, through pipe 22 controlled by valve 23, into the measuring receptacle 9. The charging tank 20 should be of such capacity or filled to such a depth that the volume of water discharged into the measuring container will be slightly greater than the volume of void space present in the sand when filled to the top of said container, in order to insure the complete saturation of the sand. To make certain of this amount I provide the preliminary measurement of the water by means of a convenient overflow arrangement in tank 20, comprising a section of pipe 25^a (see Figs. 4 and 5) swiveled at 25^b to an outlet or discharge pipe 25, a handle or lever 20^a with a pointer 20^b being connected with the pivoted piece of pipe to raise or lower its end 25^c in the tank, the pointer 20^b indicating by a scale 20^c, on the side of the tank, the amount of water in gallons or cubic feet which will be measured out in the tank 20 before discharge through pipe 22 and valve 23 to the sand and water measuring receptacle 9.

There is provided an additional or excess water tank 24, for supplying any predetermined additional quantity of water to the mix over and above that which enters the mix in the container of saturated sand, in cases where the specifications call for concrete of a greater water content. This tank 24 may be conveniently filled from tank 20 through the overflow pipe 25, and the water discharged through any suitable pipe 26 to the point of mixing. If preferred, tank 24 may be filled from a separate source of supply independent of the pipe 25. The capacity of the tank 24 is adjustable as by means of the inner box or cylinder 27 which is mounted on a threaded rod 28 movable vertically by the hand wheel 29 supported from a cross bar or frame 30. An overflow spout or lip 31 is provided on the tank 24 for discharge of the surplus water when the tank is filled.

Delivery of sand to the receptacle 9 is through the mouth 10 of the bin in which is located a grate-like sifter gate 11, or other suitable means for feeding the sand in a

shower-like manner, the elements of the shaker being oscillated or moved by the arms 12 connected through the bar 13 to the shaker handle 14. Between the hopper mouth 10 and the container 9, and operating preferably with close clearance relative to the top of the latter, is a strike-off gate 15, which may be trough-shaped, having sides 16 to prevent loss of sand from the delivery mouth 10. The gate is preferably mounted for its sliding movement on rollers 17, and is equipped with a rack 18, actuation thereof being accomplished by means of the crank 19 operating a pinion in engagement with the rack.

The measuring receptacle 9, (see Figs. 1 to 3) which receives the water and sand, is, as before stated, pivotally mounted at 6, with its open upper end adjacent the bottom of the strike-off gate 15. It has at one side an overflow spout or lip 32, to carry off the surplus water displaced when the sand is sifted into it, this spout being positioned to deliver to a trough 33 so that all surplus water may be conveniently carried off for disposal or use. The pivots 6 are so positioned on the container that they are above its center of gravity when it is empty, and below it when full, so that its movement to dumping position, as indicated by the dotted line at 34, Fig. 1, and back to filling position will be accomplished by gravity, upon the release of the latches 35, 35^a, and 36, 36^a, respectively, (see Figs. 1 and 3), which are adapted to engage automatically when the receptacle swings to filling or discharging position.

Referring particularly to Fig. 2, it will be seen that the measuring receptacle is adjustable as to volume by means of a movable bottom 45, actuated by a screw-rod 46 operating in a protecting casing 47 and adapted to be turned by the wheel 48. The rod is fixed as against vertical movement by the engagement of a collar 49 and the hub of the wheel 48 with a yoke 50 supported from the external flange 51 on the container. Leakage between the inside of the container wall and its movable bottom is prevented by a gasket or piece of rubber hose 52 compressible by a ring 53 supported by a spider 54 which is adjustable by a wing-nut 55. The bottom 45, of the container is equipped with one or more spaced plates 56 for the retention or pocketing of sufficient water to insure the thorough "washing out" of the saturated sand when dumped. There is provided also between the bottom and one of said plates a restricted drainage port 57 having a valve 58, the purpose of this being to permit the drawing off of a portion of the water without taking the sand with it, in those cases where the specifications call for a concrete of less water content than would result with complete inundation of all the sand.

For the cushioning of the discharge, and for the proper balance of the receptacle on its

pivots, the following mechanism is provided. A variable counterweight, for example a bucket 37, which may contain sand or other material to the amount required, is hung from a cable 38 run over suitable sheaves 39, 40, the other end of the cable being attached to the bottom of the container. The counterweight is made variable in order to provide for adjustments to compensate for different 5 positions of the adjustable bottom of the measuring container. As shown in Fig. 1, the counterweight 37 and sheave 40 may be so located that the same counterweight serves to retard the rotary motion of the container 10 15 20 25 30 35 40 45 50 55 60 65

9, at or near the extremes thereof, in each direction; and by shifting the position of the sheave 40 an adjustment of the relative amount of shock absorbed in the two opposite directions may be made. The exact location of sheave 40 should preferably be a matter of adjustment, subject to change when the capacity of receiver 9 is changed, by adjusting the position of its bottom, or it may be desirable in some cases to employ more than one counterweight 37 and set of sheaves 39 and 40 as local conditions may determine. Further cushioning of the shock of discharge in the arrangement shown in Fig. 1 is provided by the spring 41. When the cable 38 is pulled upwards by the rotation of the container, the clip or button 42 above the counterweight engages the spring-guiding or supporting pipe 43 and moves it upward against the compression of the spring. It will be understood of course that the pipe has freedom for sliding movement up and down in an opening in the supporting structure 44. Obviously other convenient shock absorbing mechanism may be used, and for measuring 40 receptacles of greater size and capacity than that represented in Fig. 1, I may employ, for example, a suitable dashpot construction.

The operation of the complete apparatus is as follows:

45 The charging tank 20 is filled with water, slightly more than sufficient to saturate a full load of sand in receiver 9, and valve 23 is opened to discharge the water into the receptacle. The shaker gate handle 14 is then 50 oscillated causing sand to sift down into the receptacle where it settles in the water, completely inundated. The shaking is continued until no more sand can be shaken in, at which time the receptacle will be filled to the top 55 with saturated sand, the surplus water displaced flowing out the spout 32. The strike-off gate 15 is now closed. This insures the cutting-off of the sand at exactly the same level for each load regardless of the volume 60 adjustment as made by means of the movable bottom, and thus it will be seen that no time need be wasted or great care used in filling the receptacle, the strike-off gate automatically providing accuracy. The latch bar 35 65 is now tripped and the receptacle swings by

gravity to the dumping or discharge position, the latch bar 36 then engaging the latch member 36a and holding the receptacle in discharge position while the saturated sand is emptied therefrom into any apparatus which 70 may be therebelow, such as a concrete mixer, or, if the mixing is to take place at a remote point, into a water tight truck body, or conveyor. The water trapped between the bottom 45 and the plates 56 runs down the walls 75 of the inverted container and insures the complete discharge of the material, after which, upon tripping of the latch bar 36, the container swings back to filling position by its own weight assisted by the momentum imparted by the counterweight 37. It will be apparent from Fig. 1 that the arrangement of the counterweight and the sheaves 39 and 40 is such that the initial turning moment 80 towards dumping position is augmented by the weight but that the final movement of it is retarded thereby, and any substantial shock 85 is obviated by the spring 41.

As previously indicated, where the specifications call for more water in the mix than 90 would be contained in the saturated sand, an additional measured quantity may be added to each batch from the excess water tank 24, which is adjustable in volume, through the pipe 26. Where the specifications call for 95 less water than that necessary to completely fill the voids in the sand, the desired reduction may be made by drawing off water from the container through drainage outlet 57 and valve 58, before the dumping of the charge. 100 With the arrangement of the plates 56 in the bottom of the measuring tank together with a comparatively restricted outlet it is quite practicable to draw off as much as two gallons of water in 20 or 30 seconds (which is 105 about the maximum ever required to be withdrawn) without any appreciable amount of sand being drawn off with it.

From the foregoing description of the apparatus and its operation it will be obvious 110 that I am enabled to obtain both rapid and accurate measurement of the sand and water, the two most variable elements in concrete manufacture, and maintain the concrete constant from batch to batch, the actual percentage of variation being not more than $\frac{1}{2}$ of 1 per cent. of sand, by weight, and not more than 1 or $1\frac{1}{2}$ per cent. of water, by weight; that the apparatus can be very conveniently and compactly mounted and used, 115 in connection with existing equipment; that adjustment of volume may be readily made without altering the accuracy of the measurement obtained by the use of the strike-off gate; that proper empty and load balance 120 may be maintained throughout the range of the volume adjustment, by an equivalent adjustment of the counterweight; and that by the preliminary measurement of the water in 125 tank 20 there is insured a sufficient quantity 130

of water to saturate the sand in tank 9 without appreciable surplus and that waste is thereby avoided.

I claim:—

5. Measuring apparatus comprising, in combination, a sand and water measuring receptacle, means for admitting water thereto, sand-discharging means above said receptacle, and a strike-off gate between the sand-discharging means and the receptacle. 70
10. Measuring apparatus comprising, in combination, a sand and water measuring receptacle, water-admission means therefor, a sand-sifter above the receptacle, and a strike-off gate between the sifter and receptacle. 75
15. A measuring and discharging receptacle having pivot means below its center of gravity when loaded, mechanism thereabove adapted to sift granular material thereinto, and a strike-off gate therebetween. 80
20. A measuring and discharging receptacle having fixed pivot means located below its center of gravity when loaded but above its center of gravity when empty, mechanism thereabove adapted to sift granular material thereinto, and a strike-off gate therebetween. 85
25. A measuring and discharging receptacle having fixed pivot means located below its center of gravity when loaded but above its center of gravity when empty, mechanism thereabove adapted to sift granular material thereinto, and a strike-off gate therebetween. 90
30. A measuring and discharging receptacle having fixed pivot means located below its center of gravity when loaded but above its center of gravity when empty, mechanism thereabove adapted to sift granular material thereinto, a strike-off gate therebetween, and releasable latch means for holding the receptacle in measuring or in discharging position. 95
35. In apparatus of the character described, the combination of a pivoted container, a strike-off gate thereabove, a material-sifting gate above the strike-off gate, and means for adjusting the effective volumetric capacity of the container without affecting the relative positions of the container, the strike-off gate, and the sifter-gate. 100
40. In combination, in measuring apparatus, a receiving and discharging receptacle having a receiving opening, means for delivering material thereinto, strike-off mechanism between said means and said opening, and means for altering the volumetric capacity of the receptacle without altering the relative positions of the strike-off mechanism and the opening. 105
45. In combination, in measuring apparatus, an open-topped receiving and discharging receptacle, material-delivering mechanism thereabove, a strike-off gate therebetween located in juxtaposition to the open top of the receptacle, and means for altering the effective volumetric capacity of said receptacle without altering the space between the gate and the top of the receptacle. 110
50. In combination, in measuring apparatus, an open-topped receiving and discharging receptacle, material-delivering mechanism thereabove, a strike-off gate therebetween located in juxtaposition to the open top of the receptacle, and means for altering the effective volumetric capacity of said receptacle without altering the space between the gate and the top of the receptacle. 115
55. In combination, in measuring apparatus, an open-topped receiving and discharging receptacle, material-delivering mechanism thereabove, a strike-off gate therebetween located in juxtaposition to the open top of the receptacle, and means for altering the effective volumetric capacity of said receptacle without altering the space between the gate and the top of the receptacle. 120
60. In combination, in measuring apparatus, an open-topped receiving and discharging receptacle, material-delivering mechanism thereabove, a strike-off gate therebetween located in juxtaposition to the open top of the receptacle, and means for altering the effective volumetric capacity of said receptacle without altering the space between the gate and the top of the receptacle. 125
65. In combination, in measuring apparatus, an open-topped receiving and discharging receptacle, material-delivering mechanism thereabove, a strike-off gate therebetween located in juxtaposition to the open top of the receptacle, and means for altering the effective volumetric capacity of said receptacle without altering the space between the gate and the top of the receptacle. 130
- located in juxtaposition to the open top of the receptacle, and means for altering the effective volumetric capacity of said receptacle without altering the space between the gate and the top of the receptacle, said means comprising a movable bottom in the receptacle.
10. In mechanism of the character described, the combination of a container, pivot means between the ends thereof about which it is adapted to revolve, an adjustable bottom therein, and dewatering means in said bottom.
11. In mechanism of the character described, the combination of a sand and water container, pivot means between the ends thereof about which it is adapted to revolve, an adjustable bottom therein, and water-drainage means in said bottom together with means adapted to prevent any substantial draining off of sand through said drainage means.
12. In mechanism of the character described, the combination of a sand and water container, fixed pivot means between the ends thereof about which it is adapted to revolve, an adjustable bottom therein, and a sand-excluding water pocket in said bottom.
13. A material measuring and dumping container having a pivotal mounting located above its normal center of gravity when empty but below it when loaded, together with shock-absorbing means operable when the container is dumped, or returned to normal position.
14. A material measuring and dumping container having a pivotal mounting located above its normal center of gravity when empty but below it when loaded, together with shock-absorbing means operable when the container is dumped or righted, and latching means automatically locking said container at either limit of its motion.
15. The combination of a pivotal material measuring and dumping container having volume adjusting means, and an adjustable counterweight in association with said container.
16. The combination of a pivoted material measuring and dumping container having volume adjusting means, and an adjustable shock-absorbing counterweight in association with said container, together with additional shock-absorbing means adapted to cushion the dumping and righting of the container near its limit of motion.
17. In apparatus for the measuring of sand and water for mixture in concrete batches, the combination of an adjustable measuring container for inundated sand and an adjustable preliminary water measuring container with means for discharging the measured water into said first-mentioned container.
18. In apparatus for the measuring of sand and water for mixture in concrete batches, the combination of an adjustable measuring container for inundated sand and an adjust-

- able preliminary water measuring container with means for discharging the measured water into said first-mentioned container, together with an auxiliary water measuring container for adding water to the batch.
- 5 19. In apparatus for the measuring of sand and water for mixture in concrete batches, the combination of an adjustable measuring container for inundated sand and an adjustable preliminary water measuring container with means for discharging the measured water into said first-mentioned container, together with an auxiliary water measuring container, the first and last-mentioned containers having means for discharging their contents to a common point of mixing.
- 10 20. In apparatus for the measuring of sand and water for mixture in concrete batches, the combination of an adjustable measuring container for inundated sand and an adjustable preliminary water measuring container with means for discharging the measured water into said first-mentioned container, together with an auxiliary water measuring container, adapted to be filled either from said preliminary water measuring container or a separate source of supply.
- 15 21. In apparatus for the measuring of sand and water for mixture in concrete batches, the combination of an adjustable measuring container for inundated sand and an adjustable preliminary water measuring container with means for discharging the measured water into said first-mentioned container, together with an auxiliary water measuring container for adding water to the batch and valve means controlling the filling and discharging of said containers.
- 20 22. In apparatus of the character described, a preliminary water measuring container, a sand and water measuring and dumping container, water overflow means for each container, and water discharging means from the first container to the second.
- 25 23. In apparatus of the character described, a preliminary water measuring container, a sand and water measuring and dumping container, water overflow means for each container, and water discharging means from the first container to the second together with an auxiliary water measuring container adapted to discharge substantially at the point of discharge of the said second container.
- 30 24. In apparatus of the character described, a preliminary water measuring container, a sand and water measuring and dumping container, water overflow means for each container, and water discharging means from the first container to the second together with an auxiliary water measuring container adapted to discharge substantially at the point of discharge of the said second container, the overflow means of said first
- 35 container discharging into the auxiliary container.
- 40 25. In apparatus of the character described, a preliminary water measuring container, a sand and water measuring and dumping container, water overflow means for each container, and water discharging means from the first container to the second together with an auxiliary adjustable water measuring container having an overflow means for surplus water and adapted to deliver its measured quantity of water at the point of discharge of the said second container.
- 45 26. In apparatus for measuring granular material and water, material delivery means, a container supported in substantially fixed relation thereto, gate means for controlling the delivery of material, and water overflow means on said container having directed discharge below the top thereof.
- 50 27. In apparatus for measuring granular material and water, material delivery means, a container supported in substantially fixed relation thereto, gate means for controlling the delivery of material, and water overflow means on said container, having directed discharge below the top thereof, together with means for adjusting the capacity of the container.
- 55 28. In apparatus for measuring granular material and water, material delivery means, a container supported in substantially fixed relation thereto, gate means for controlling the delivery of material, and water overflow means on said container having directed discharge below the top thereof, together with means for adjusting the capacity of the container below the overflow level.
- 60 29. In apparatus for measuring granular material and water, material delivery means, a container supported therefrom, gate means for controlling the delivery of material, and water overflow means on said container having directed discharge below the top thereof.
- 65 30. In apparatus for measuring granular material and water, material delivery means, a container supported therefrom, gate means for controlling the delivery of material, and means for withdrawing water from the container while normally loaded.
- 70 31. In mechanism of the character described, a movable measuring container having a trap constructed to hold water and exclude sand when the container is in filling position and to discharge water when it is in emptying position, together with water-drainage means below the container top operable when said container is in the said filling position.
- 75 32. In a device for measuring sand and water to be used in the making of concrete, the combination of a sand supply means, a receptacle suspended in juxtaposition thereto, means for introducing water into said re-
